MUSICAL INSTRUMENT

Richard Culbertson, Manlius, N.Y., assignor to
General Electric Company

Filed Feb. 25, 1971, Ser. No. 119,069

Term of patent 14 years

Int. Cl. D17—01

U.S. Cl. D56—2

FIG. I

FIG.2

FIG.3

FIG.4

FIG.5

FIG.6

FIG.7

FIG.8

FIG. 1 is a front, top and right side perspective view of a musical instrument, showing my new design with the cover opened;

FIG. 2 is a front, top and left side perspective view with the cover closed.

FIG. 3 is a rear elevational view with the cover closed;

FIG. 4 is a left side elevational view with the cover opened;

FIG. 5 is a right side elevational view with the cover closed;

FIG. 6 is a top plan view with the cover removed and omitted for convenience in illustration;

FIG. 7 is a bottom plan view; and

FIG. 8 is a front elevational view thereof with the cover closed.

I claim:

The ornamental design for a musical instrument, as shown.
